(57) **CLAIM**

The ornamental design for a stomach-shaping garment as shown and described.

DESCRIPTION

FIG. 1 is a front elevation view of the stomach-shaping garment.

FIG. 2 is a rear elevation view thereof.

FIG. 3 is a left side elevation view thereof.

FIG. 4 is a right side elevation view thereof.

FIG. 5 is a top plan view of the claimed design.

FIG. 6 is a bottom plan view of the claimed design; and, FIG. 7 is a perspective view with additional environment. The cross-hatch pattern sporadically depicted throughout the views is intended to indicate that the pattern is continuous throughout the surface on which the pattern is shown.

1 Claim, 6 Drawing Sheets
